COMBINED ASH TRAY AND BUBBLE LEVEL OR SIMILAR ARTICLE

David Murdock, Cincinnati, Ohio

Application June 23, 1954, Serial No. 31,128

Term of patent 7 years

(Cl. D85—2)

Fig. 1

Figure 1 is a perspective view of a combined ash tray and bubble level or similar article showing my new design; and

Portions of the drawing are diagonally lined to indicate transparency.

I claim:

The ornamental design for a combined ash tray and bubble level or similar article, substantially as shown and described.
